Primary Examiner — Deanna L Pratt

(74) Attorney, Agent, or Firm — Simpson & Simpson,
PLLC(57) **CLAIM**

The ornamental design for a photo display device, as shown and described.

DESCRIPTION

FIG. 1 is a front perspective view of the photo display device of the present invention;

FIG. 2 is a rear perspective view of the photo display device of the invention shown in FIG. 1;

FIG. 3 is a front elevational view of the invention shown in FIG. 1;

FIG. 4 is a rear elevational view of the invention shown in FIG. 1;

FIG. 5 is a left side elevational view of the invention shown in FIG. 1;

FIG. 6 is a right side elevational view of the invention shown in FIG. 1;

FIG. 7 is a top plan view of the invention shown in FIG. 1; and,

FIG. 8 is a bottom plan view of the invention shown in FIG. 1.

A photo display device is shown in FIGS. 1 and 3 which show images of three people in broken lines to show the invention in context only and the broken lines form no part of the design to be patented.
